COIN SELECTOR

Russell J. Donohue, Cambridge, Ohio

Application July 19, 1949, Serial No. 105,605

3 Claims. (Cl. 194—97)

1

My invention relates to coin selectors and has particular reference to apparatus of this character wherein a movable gate is employed, as illustrated in Patent 2,292,628.

In Patent 2,292,628, when a rejected coin is introduced into the apparatus, the operator must first manually operate the apparatus to clear the same and eject or return the rejected coin, if any, prior to the insertion of the accepted coin. The clearing is effected by manually operating a lever or scavenger which sweeps the rejected coin from proximity to the magnet if held thereby, and also shifts the gate to the open position whereby the pusher will insure the return of the rejected coin if it is held by the coin testing means. The disadvantage of this construction is that it places upon the operator the necessity of manually operating the apparatus to clear the same for the return of rejected coins.

In accordance with my invention, the gate is biased open instead of biased closed as is shown in Patent 2,292,628. In operating my selector apparatus, when the coin is inserted into the slot, a coin actuated switch is closed. The closing of this switch causes a circuit to be closed and time controlled means is provided to maintain the circuit closed for a selected period and then automatically open the same. When the circuit is closed, electrically operated means is energized which shifts the gate to the closed position and the gate will remain in the closed position for a sufficient length of time to permit of the passage through the apparatus of the accepted coin. However, the rejected coin will not pass through the apparatus within this selected period, and since the gate is biased open, at the end of this period the gate moves to the open position and hence the coin is returned to the operator. The electrical means which shifts the gate to the closed position is an electromagnet or electromagnets and also serves to test the coin and hold rejected coins.

In the accompanying drawings, forming a part of this application, and in which like numerals are employed to designate like parts throughout the same,

Figure 1 is a side elevation of the gate and associated elements included in the coin selector,

Figure 2 is a horizontal section taken on line 2—2 of Figure 1, showing the gate in the open position,

Figure 3 is a similar view showing the gate in the closed position,

Figure 4 is a side elevation of the gate and guide plate, viewed from the opposite side from that shown in Figure 1, parts broken away,

2

Figure 5 is a diagrammatic view showing the circuits included in the apparatus,

Figure 6 is a side elevation of the coin actuated switch, and,

Figure 7 is a central vertical section through a time controlled device.

The coin selector comprises a main plate 10 which is vertical and has flanges 11. Arranged upon the inner face of the main plate 10 and spaced therefrom for a suitable distance to accommodate the coins of the maximum thickness is a guide plate 12, having knuckles 13 hinged upon a pin 14, engaging knuckles 15, carried by one flange 11. The guide plate 12 when in the inner position is parallel with the main plate 10, and is retained spaced from the main plate by a lug 16 engaging an extension 17 of the guide plate. The guide plate has notches 18 and 19 formed therein.

20 The device further comprises a gate 20, having arms 21, hinged upon the vertical pin 14 to swing horizontally. This gate carries an upper inclined coin track 22 and a lower inclined coin track 23, which project laterally beyond the inner face of the gate. The coin track 22 extends through the notch 18 and the coin tract 23 enters the notch 19.

25 The gate carries an upper device for testing coins for size and weight, such as quarters, and this device includes a cradle 24, arranged upon the outer face of the gate and pivoted at 25. This cradle has a weight 26. The cradle has laterally projecting fingers 27 and 28, operating within slots 29 and 30 respectively. The gate carries a lower device for testing smaller coins 35 for diameter and weight, such as nickels. This device includes a vertically swinging arm 31, pivoted to the gate at 32 and this arm has a weight 33. The arm 31 is provided at its upper end with a laterally projecting finger 34 extending beyond the inner face of the gate and arranged opposite to an upstanding flange or track 35. The upper end of the arm 31 is arranged to engage a horizontal crank formed upon a vertical wire or rod 36 mounted upon the gate to turn upon its longitudinal axis, and this rod is provided at its lower end with a crank 37 having an extension 37' at a right angle thereto and projecting into the path of travel of the coin passing between the extension 34 and the track 35. The 40 shaft 36 is biased so that the extension 37' normally projects into the path of travel of the coin, and this is accomplished by having the crank at the upper end of the rod 36 engaged by a vertically swinging lever 38, which is weighted at 45 its lower end.

50

The device further comprises a pusher 39 pivoted upon the pin 14 and carrying a leaf spring 40 engaging the flange 11 and holding the pusher parallel with the main plate 10, the inward movement of the pusher being limited by the lug 41, secured to the guide plate. The pusher has a head 42, provided with laterally projecting fingers 43 and 44. The finger 43 is adapted to project into the slot 38, while the finger 44 is adapted to project into a slot 39.

The coin selector device thus far described is substantially the same as that shown in Patent 2,292,628 issued to B. W. Fry, August 11, 1942.

In accordance with the present invention, the gate is biased open and for this purpose the free end of the gate engages a spring 45, having its upper end fixedly attached to the main plate 10.

An electromagnet 46 is mounted upon the main plate 10 to act upon the quarters passing down the track 22 and an opposed armature 47 is mounted upon the guide plate 12. A lower electromagnet 48 is mounted upon the main plate 10 and has poles 49 and an opposed electromagnet 49 is mounted upon the gate 20 and has poles 49' and the opposed magnets 48 and 49 act upon the nickels travelling down the track. The poles 49' are movable into and out of openings 50' formed in the plate 12. The adjacent poles of the electromagnets 48 and 49 are of opposite polarity and these magnets therefore attract each other and when energized the electromagnet 49 swings the gate to the inner position but when the electromagnets are de-energized the spring 45 swings the gate to the open position.

A coin chute 50a leads from a coin slot 50 formed in a plate 51' and delivers the coin to a vertical passage 51 which directs the coin to the cradle 24. A vertically swinging lever 52 is pivotally mounted upon a fixed pivot 53 secured to the plate 51', and has apertured knuckles 54, pivotally receiving an upstanding arm 55 to turn upon its longitudinal axis. The arm 55 carries a coin engaging head 56 which extends over the upper portion of the coin slot, and the head 56 is biased downwardly by a spring 57. The head 56 is vertically adjustable to accommodate coins of different diameters and when the coin is inserted into the slot 50 the head is elevated and is also swung laterally about the axis of the arm 55. When the head 56 is shifted laterally, it engages an insulating strip 56' carried by a contact leaf spring 57 to engage and disengage a leaf spring 59, mounted upon an insulating block 59', secured to the plate 51'. The leaf springs 57 and 59 constitute a switch which is biased open.

The numeral 60 designates a solenoid winding included in a timing device for controlling the closing of a switch which is biased closed. This time device includes a core 61 slidable in a casing 62 and having a substantially air tight fit therein. The casing 62 has a contracted port 63 and an adjustable screw 64, to partly cover the port. The core 61 moves down by gravity and the winding 60 is held stationary. When the core 61 descends it engages an insulating strip 65, mounted upon a leaf spring contact 66, which is biased closed to engage an upper leaf spring contact 67, both leaf springs being carried by a stationary insulating block 68.

The numerals 69 and 70 designate lead wires. The lead wire 69 is connected with the leaf spring 57 and a wire 71 is connected with the leaf spring 59 and with one end of the solenoid winding 60, the opposite end of which is connected with the lead wire 70. A wire 72 is connected with the

lead wire 69, and is connected with the leaf spring 66, and a wire 73 is connected with the leaf spring 67. The wire 73 has the electromagnets 46, 48 and 49 connected in series therein and the wire 73 is connected with the lead wire 70.

The operation of the coin selector apparatus is as follows: The coin control switch is normally open and the solenoid winding 60 accordingly de-energized so that the core 61 holds the contact leaf spring 66 in the lowered opened position and the circuit including the electromagnets is open at the contact leaf springs 66 and 67. The spring 45 now holds the gate in the open position. With the parts thus adjusted, if an accepted coin, such as a quarter, is inserted into the slot 50, the contact leaf springs 57 and 59 will engage and a circuit will be closed which energizes the solenoid winding 60, and the core 61 is quickly elevated. The contact leaf spring 66 now moves up and engages contact leaf spring 67 and a circuit is closed including the electromagnets. When the coin is introduced into the slot 50, the coin control switch is instantly closed and the switch including leaf springs 66 and 67 quickly close. When the coin leaves the slot 50 it enters the coin chute 50a and then passes into the vertical passage 51. The coin actuated switch opens but the switch including contact springs 66 and 67 remains closed until opened by the downward movement of the core 61. The electromagnet circuit is therefore closed and will remain closed for a selected period, which is determined by the time required for the core 61 to descend to the lowermost position. When the electromagnet circuit is closed, the gate is swung to the inner position, which occurs before the coin reaches the passage 51, and the gate is held in the closed position a sufficient length of time to permit the accepted coin, such as a quarter, to pass through the apparatus. The cradle 24 tests the coin for diameter and weight. Assuming that a fiber disc were inserted into the apparatus instead of an accepted quarter, then the fiber disc or rejected coin would be held within the apparatus by the cradle 24, and at the end of the period for holding the gate closed, the gate would automatically open and the rejected coin returned to the operator. Assuming that the rejected coin had the diameter of a quarter and was of sufficient weight to tilt the cradle 24 but was formed of iron, then this rejected iron coin would be caught between the electromagnet 46 and armature 47 and held at that position. At the end of the period for which the gate was held closed, the gate would then automatically open and the rejected iron coin return to the operator. In a similar manner, an accepted coin, such as a nickel, may pass through the apparatus during the period that the gate is held closed, but if a rejected coin having the diameter of a nickel is inserted into the apparatus, it will be tested for weight and material, and if rejected it will be held in the apparatus and when the gate opens it will be returned to the operator. The operation of the testing devices is fully described in said Patent 2,292,628 and no further explanation is thought necessary. This patent also presents additional tests which do not involve the opening or closing of the gate. While I have shown my invention as applied to a selector apparatus of the character shown in Patent 2,292,628, yet it is not necessarily restricted to the precise coin testing devices shown therein, as I contemplate embodying my invention in a coin selector having a

swinging gate which may be equipped with different types of coin testing device or devices.

The invention is in the nature of an attachment for a coin selector mechanism.

Since the gate is normally biased open, the rejector will automatically reject all coins when current is turned off from the machine and mechanism.

The rejector automatically returns bad coins to the operator, when the time cycle is up for the coin to pass through the rejector, due to the fact that the gate is biased open and the electromagnets will be de-energized at the end of the time cycle.

It is to be understood that the form of my invention herewith shown and described is to be taken as a preferred example of the same, and that various changes in the shape, size and arrangement of parts, may be resorted to without departing from the spirit of the invention or the scope of the subjoined claims.

Having thus described my invention, I claim:

1. A coin selector mechanism comprising a relatively stationary plate, a pivoted gate arranged upon one side of the plate and movable to closed and opened positions with respect to the plate and having a track to be moved close to the plate when the gate is in the closed position, the plate, gate and track forming a coin chute when the gate is in the closed position, a spring to bias the gate to the open position so that the coin supported by the track will fall from the track, an electromagnet mounted upon the gate and when energized serving to move the gate to the closed position and also serving when energized to hold a rejected magnetic coin fed upon the track and to release said rejected magnetic coin when de-energized, a circuit connected with the electromagnet, time-controlled means to open and close the circuit, and coin operated means to actuate the time-controlled means.

2. A coin selector mechanism comprising a relatively stationary plate, a guide plate disposed near and upon one side of the stationary plate and having a notch and an opening formed therein, a pivoted gate disposed upon the same side of the plate with the guide plate and movable to closed and opened positions with respect to the plate and having a track extending into the notch and to be moved close to the plate when the gate is in the closed position, the relatively stationary plate, gate and track forming a coin chute when the gate is in the closed posi-

tion, a spring to bias the gate to the open position so that the coin supported by the track will fall from the track, an electromagnet mounted upon the gate and having a pole extending through the opening the guide plate to be arranged close to the coin supported upon the track when the gate is in the closed position, said electromagnet serving to swing the pivoted gate to the closed position when energized and also serving when energized to hold a rejected magnetic coin fed up on the track and to release said rejected magnetic coin when de-energized, means to energize the electromagnet for a selected period and then de-energize the same, the coin being released when the electromagnet is de-energized and the gate simultaneously swung to the opened position by the spring.

3. A coin selector mechanism comprising a relatively stationary plate, a pivoted gate disposed upon one side of the plate and movable to closed and opened positions with respect to the plate and having a track to be moved close to the plate when the gate is in the closed position, the relatively stationary plate, gate and track forming a coin chute when the gate is in the closed position, a spring to bias the gate to the open position so that the coin supported by the track will fall from the track, magnetic means including a pair of oppositely arranged electromagnets, one electromagnet being mounted upon the gate and the other electromagnet being mounted upon the plate, the electromagnets being arranged near the track, said electromagnets when energized serving to swing the pivoted gate to the closed position and also serving when energized to hold a rejected magnetic coin upon the track and to release said rejected magnetic coin when de-energized, means to energize the electromagnets for a selected period and then de-energize the same, the rejected magnetic coin being released when the electromagnet is de-energized and the gate simultaneously swing to the open position by the spring.
